ATTORNEY.

UNITED STATES PATENT OFFICE.

BENJAMIN F. SPARR, OF BROOKLYN, NEW YORK.

WASHING APPARATUS FOR DISHES, &c.

1,281,864.

Specification of Letters Patent. Patented Oct. 15, 1918.

Application filed December 12, 1917. Serial No. 206,755.

To all whom it may concern:

Be it known that I, BENJAMIN F. SPARR, a citizen of the United States, and a resident of the borough of Brooklyn, county of 5 Kings, city and State of New York, have invented certain new and useful Improvements in Washing Apparatus for Dishes, &c., of which the following is a specification.

Although applicable to the washing of various articles my improvements are especially adapted for embodiment in dish washing machines and the like, in which rapid and thorough cleansing is a desideratum. Heretofore gravity sprays have been resorted to 10 in such apparatus to effect the initial removal of the extrinsic matter and the subsequent rinsing of the articles, but that method is lacking in power and efficiency. One of the objects of my invention is to augment the impact of the sprays of water used for both purposes and at the same time to provide for the regulation of force in accordance with the character and requirements of the articles under treatment so that 15 fragile and delicate objects may be subjected to pressure less strenuous than that which can safely be applied to stronger and coarser objects. Another object of the invention in this connection is to control the speed of 20 treatment manually by means of a crank by which the feed of the work carrier may be accelerated or retarded, as found most expedient. Another feature of the invention is the spraying of the articles simultaneously 25 from below as well as from above so as to render the cleansing more rapid and effective,—the invention consisting in the combination and arrangement of parts described 30 and claimed specifically, the operation of 35 which will be hereinafter more fully set forth.

In the accompanying drawings,

Figure 1, is a vertical longitudinal sectional elevation of apparatus embodying the 40 essential features of my invention, taken upon plane of line 1—1, Fig. 3;

Fig. 2, is a section taken upon plane of line 2—2, Figs. 1 and 3;

Fig. 3, is an end elevation of the apparatus;

Fig. 4, is a sectional elevation taken upon plane of line 4—4, Fig. 1, but on a larger scale.

The elongated tank T, is supported on

standards t, and is divided by a transverse 55 partition t', into the compartments T' and T''. The outer ends of these tank compartments T', T'', are each provided with a hinged cover t'', the free ends of which rest normally on stops t''. Between these outer 60 end covers t'', is the wash chamber C, closed at the top and sides, but communicating below with the tank compartments T', T'', over the inner ends of which the wash chamber C, 65 extends as shown more particularly in Fig. 1.

The ends of the wash chamber C, are provided with doors c, c, hinged so that they may be swung into horizontal position to act as end platforms or tables to facilitate the handling of the articles to be treated. In 70 the drawings these doors are fulcrumed on the shafts a, a, and are formed with rests c', c', which contact with the tank covers t'', when the latter are closed and the doors c, c, are open, as in Figs. 1 and 3. The doors 75 c, c, are also preferably formed with side members or wings c² c², which act as guards and fenders when the doors are open and in use as tables or platforms.

The shafts a, a, mounted transversely, one 80 at each end of the wash chamber C, carry pulleys a', a', over and between which endless carriers b, b, travel, said carriers being also supported medially by idlers a², a². A 85 crank a³, secured to one of the shafts a, affords means for manually driving the endless carriers b, b, which may consist of parallel twin belts, one on each side of the wash chamber C, on which open work trays or baskets (containing the articles to be 90 washed) may be placed, thus leaving the space between the belts b, b, free for the passage of the cleansing fluids; or any other form of open work carrier may be substituted that will admit of the requisite flow 95 and circulation of cleansing fluids.

The compartment T', of the tank contains the primary cleansing fluid solution such as water and solvent compounds dissolved therein, to facilitate the removal of grease 100 and other foreign substance from the surfaces of the articles to be cleaned,—the level of this primary cleansing fluid in said compartment T', being determined by the drain stand pipe d, which conducts the overflow 105 through the discharge pipe d', to the waste or sewer pipe d''. In like manner a drain stand pipe d'', in the other compartment T'',

of the tank determines the level of the rinsing liquid therein, said drain stand pipe d^4 , communicating with the sewer or waste pipe d^6 , through the medium of the discharge pipe d^5 . The bottom of each compartment of the tank is also provided with a drain d^7 , controlled in each case by a valve d^8 , said valves connecting respectively with the discharge pipes d' , and d^5 , as shown particularly in Fig. 1.

P , is a fluid pressure pipe provided with a control valve p . Connected with this fluid pressure pipe P , is the vertically disposed pressure pipe p' , in the primary or cleansing solution compartment T' , and the vertically disposed pressure pipe p^2 , in the rinsing solution compartment T^2 . E , is an ejector attached to the pressure pipe p' , in the primary solution compartment T' , and shown in detail in Fig. 4, although I do not confine myself to any particular form or construction of ejector, the main function of which is the utilization of the fluid pressure to suck in and force the solution from the compartment T' , to and through the supply pipe e , and its branch e' , to the pressure shower pipes e^2 , e^2 , positioned in the upper part of the wash chamber C . Any desired number of these shower pressure pipes e^2 , e^2 , may be provided according to the size and capacity of the apparatus and the particular purpose for which it is intended. Manifold ejectors E' , E' , are also attached to the transverse pressure pipe p'' , in the primary compartment T' , formed each with a series of ejector nozzles e'' , similar in construction and operation to the ejector E , shown in Fig. 4. This series of ejector nozzles project upward and precipitate the cleansing solution against the under sides of the articles presented above them by the work carriers b , b .

E^2 , is an ejector like unto that illustrated in Fig. 4, but situated in the rinsing liquid compartment T^2 , and mounted on the pressure pipe p^2 , contained therein. In this case the ejector E^2 , not only communicates with a stand pipe e^3 , a transverse branch e^4 , and its series of pressure shower pipes e^5 , e^5 , but also with a lower transverse pressure feed pipe e^6 , carrying a series of ascending spray pipes e^7 , which project the rinsing liquid upward against the under portions of the articles immediately above them on the carriers b , b , at the same time that the pressure shower pipes e^5 , precipitate said rinsing liquid upon the upper sides thereof, thus insuring a thorough cleansing of the articles treated. The meeting of the opposed pressure sprays in the case of the primary cleansing liquid as well as in the case of the rinsing liquid renders both operations speedy and effective.

The fluid pressure supplied through pipe

P , may be either water, steam or air pressure as may be found most expedient and best adapted to the articles to be subjected to treatment; and the amount of fluid and degree of pressure introduced into the ejectors may be regulated conveniently and accurately by means of the valve p ,—the ejectors sucking in and precipitating amounts of liquid from the compartments T' , T^2 , in proportion to the pressure in a manner well known, and thereby effecting a forceful circulation of both the primary cleansing liquid and the rinsing liquid in such manner as to effectually prevent clogging of the spray or shower orifices by grease or dirt,—a source of difficulty inherent in apparatus in which gravity alone is relied upon to spray the articles treated.

The control of the feed of washable material to the pressure jets by means of the crank a^8 , is also an important factor in attaining perfection of result as the articles may be advanced continuously or intermittently, slowly or rapidly, according to circumstances and requirements. Furthermore the passing of the articles through a path in which liquid under pressure is caused to impinge against them practically on all sides owing to the meeting and concentration of the opposed sprays in said path, is an important and distinctive feature of my invention and one that renders the apparatus efficacious. It also enables me to attain a maximum of result and output within a minimum of space, since the whole arrangement is simple and compact,—the opposed sprays insuring the cleansing of the articles in a small area and short length of feed.

When the use of relatively large quantities of water is desirable water under pressure may be supplied to the ejectors; when very hot water is required, steam pressure may be found preferable; or when working under normal conditions with hot water, compressed air may be used for the purpose,—or any combination of these fluid pressures may be resorted to in certain emergencies.

I have herein shown my pressure sprays as operating and opposed vertically although it is obvious that they might be arranged horizontally or at any intermediate angle between horizontal and vertical without departing from the spirit and intent of my invention in this respect.

What I claim as my invention and desire to secure by Letters Patent is,

Washing apparatus of the character designated, comprising a tank compartment to contain a cleansing fluid, a transverse pressure pipe within said compartment, manifolds connected therewith and extended lengthwise of the tank and arranged to be

immersed in the cleansing fluid, a multiplicity of ejector nozzles carried by said manifolds and terminating above the fluid level, a supply pipe rising from said trans-
5 verse pipe, a plurality of shower pipes connected with the supply pipe, said ejectors and shower pipes arranged to spray the

fluid in opposite directions upon the articles to be cleaned, and an ejector connected with said supply-pipe.
